OSCAR L. SUENDERHAUF, OF DREXEL HILL, PENNSYLVANIA.

RAILROAD-CROSSING SYSTEM.

Application filed February 16, 1927. Serial No. 168,651.

The present invention relates to protection of railroad crossing streets or roadways. One object is to automatically operate a gate to arrest traffic in either direction of a multiple track railway and to provide means, 5 automatically controlled by the gates, to signal an engineer of an approaching train in either direction on approach at the crossing.

In carrying out the invention, I provide 10 each pair of rails with a number of consecutive insulated sections a predetermined distance in advance of the crossing, which act to consecutively operate relays on transit of a train toward the crossing, the first relay acting to open the circuit of a 15 normally lighted green signal safety lamp, the relay acted on by the second insulated section acting to close the circuit of a red danger lamp to warn vehicles approaching the crossing, and the third section acting 20 through a third relay to operate a magnet controlling a compressed air valve to act upon pistons in the gate posts to automatically lower the gates and actively restrain crossing of vehicular traffic. Simultaneously with the display of the red lamp, 25 is an audible signal continuously operated by closure of the red lamp circuit to audibly indicate to any one approaching the gate that there is a train coming in the block. At the completion of the gate lowering, an electric 30 circuit is operated displaying a safety signal at the side of the track to indicate to an engineer on an approaching train that the gate is closed, and an adjacent signal lamp 35 at the side of the track to indicate to the engineer that the automatic train stop device, forming a part of the invention, is in inoperative position and he is free to pass the crossing. The latter signal lamps are 40 controlled by the compressed air system. This train stop device, when retracted, due to bleeding of the air pressure, lies in the path of a dependent trip on the train, to 45 automatically actuate a valve on the locomotive, and operate the locomotive throttle or the brakes of the train to stop the train before reaching the crossing.

The invention involves also novel features 50 in the several types of apparatus employed. It comprises also a circuit controller mounted transversely of the tracks at the crossing by which the transit of a vehicle will automatically act to raise the gates and if it is 55 stuck on the crossing, will keep the gates

raised with the train stop device in operative position, and simultaneously by control of the signals, indicate to the engineer that there is danger ahead.

In the accompanying drawings illustrating 60 a system embodying my invention:

Figure 1 is a diagrammatic illustration of a two-way track representing a railroad crossing embodying my invention.

Figure 2 is a part sectional elevation of a 65 crossing gate according to my invention.

Figure 3 is a cross sectional view of one of the gate posts.

Figure 4 is a sectional view of a track instrument to stop a locomotive automatically. 70

Figure 5 is an elevation of the track instrument.

Figure 6 is a sectional view of a magnet for controlling compressed air.

Figure 7 is a detail view of a device to 75 stop a train.

Referring first to Figure 2, at 1 is represented a crossing at a street or roadway spanning a plurality of railway tracks. A pair of cylindrical posts 2 is arranged at 80 each side of the tracks and these posts are supported in cement or other stable foundations at the sides of the roadway. The posts are cylindrical and tubular to accommodate a pair of counter-weights 3 moving freely 85 with sufficient close fit to permit being driven upwardly by compressed air. At the side of each post is secured a vertical guide 4, 4^a to guide a vertically moving gate 5 formed of structural iron and the gate is 90 connected to the weights by cables 6, 6^a passing over pulleys 7, 7^a mounted in the guides 4, 4^a. A spring cushion, indicated at 8, elastically arrests drop of the counter-weights when air pressure is cut off from the 95 pipes 9, 9^a which branch from a supply pipe 10, the flow of air through which is controlled automatically by a magnetic valve actuated by a relay.

Mounted at the top of the fixed framework 100 on the gate is an audible signal 11 and a pair of signal lamps 12, 13. 14, 14^a indicate barriers movable with the gate to cover the sidewalks adjacent the street at the crossing to check pedestrians. Intermediate 105 the rails are a plurality of casings 16 containing compression springs 17 to support elastically a platform 18 carrying at its sides a pair of elastic metallic contacts 19, 19^a to cooperate with bracket supported contacts 110

20, 20^a to which circuit wires 21, 21^a lead into a switch from a source of electric supply, as for instance, a local supply circuit.

- 5 The connection with the tubular posts of the branch pipes 9, 9^a is through an airtight diaphragm 22. The gate 5 is provided with roller bearings 23, (see Figure 3), rolling on a smooth vertical channel beam 24 which 10 form the guide 4 or 4^a. This beam 24 is connected by a plurality of straps 25 to the post. The gate carries an insulated finger 26 which bridges two contacts 27, 27^a when the gate is lowered to complete a circuit to 15 signal lamps. In pockets formed at the sides of the beams 24 are located circuit wires 28 to which the signal lamps 12 and 13 and audible signal 11 are connected. The track instrument secured outside the tracks 20 comprises two telescoping cylinders 29 connected by a coil spring 30. An air pipe 31 communicates with the inner cylinder and when air pressure is applied, the spring is 25 distended and a trip foot 32 is shifted out of the track of a trip tongue 37 depending from a locomotive and at the same time, two contacts 33, 34 are brought into contact by one of them being engaged by the projection 36^a on the outer cylinder, to close the 30 circuit of a signal lamp R to indicate to the engineer that the track instrument is in in-operative position and that he may proceed across the crossing without being stopped. The retraction of the track instrument shifts 35 the foot to a position where it will engage the dependent locomotive valve trip and stop the train and breaks the circuit to lamp R as the contacts 33 and 34 are separated by their springs 35 and 36.
- 40 In Figure 7, the structure of one form of device for automatically stopping the engine is indicated. It comprises a pivoted arm 37 controlling the air brake system of the train or operating the locomotive throttle when 45 engaged by contact with the upstanding foot 32 when the track instrument is retracted by loss of air pressure.
- 50 The air pressure operating the gates is controlled by an electromagnetic device, one type of which is indicated in Figure 6. As here indicated, air supply from a locally operated compressor maintains pressure of air. The pipe 10 from the compressor is in open communication with a chamber forming 55 part of an electromagnet 39 and controlling, by a spring seated valve 40, another section of pipe 10 which is in communication with the gates, and when air pressure from the compressor is applied by actuation of the 60 magnet, the pistons 3 are raised and the gates lowered, showing danger ahead. The armature 41 of the magnet is mounted on a stem connecting with the valve 40 and a bleed valve 42 so that when the magnet is deener- 65 gized, the spring at the base closes the valve

40, cutting off communication with the compressor and opening valve 42, thus permitting the compressed air to bleed the air pressure and raise the gates by the counter-balancing weights. The gate operating magnet 39 is operatively related to a source of constant potential, see Figure 1, at 43, 44. The circuit controllers 21, 21^a are supported between the rails at the crossing so that in the event of a vehicle being stalled on the 75 tracks, the magnet 39 would be deenergized by opening a switch magnet circuit, as lead 60, by a magnet 61 across the supply circuit, thereby permitting the rebound of the armature under bias of its retracting spring and 80 opening the bleed valve and releasing the track instrument to stop the train. Of course, the gates would also be raised by this action of the magnetic valve.

A diagram of Figure 1 shows a wiring 85 system suitable for both directions of travel of trains. A definite distance before the gates, the rails are provided with three insulated sections 45, 46, 47, the entire series being at a sufficient distance in front of the 90 crossing to permit the approach of a train on bridging any of the sections, completing a circuit from a source of current 48 thorough one of a series of relays 49, 50, 51 and hold up their armatures consecutively as long as 95 the axles bridge the rails. The control wires between the rails and source of current 48 are preferably carried from the battery and relays located in a shed or building at the side of the tracks containing the compressor and other apparatus required to operate the 100 gate. The circuit wires are carried in surface or underground insulating conduits to their points of connection in the several 105 control circuits. The relays 49, 50, 51 are in consecutive order connected in operation by the insulated sections 45, 46, 47 and their armatures open or close the circuit of different translating devices in transit of a train. When the first axle of an approaching train 110 bridges the rails 45, 45^a, the circuit of battery 48 is completed through relay 49 by the wheel axle bridging the rails of the section and thereby operating the armature of relay 115 49 and opening the circuit of the green signal lamp 12 mounted on the gate, which in a normal unactuated condition of the relay 49 is in circuit with a supply circuit 52, 52^a. Under normal conditions, this relay closes the green lamp circuit and signals to a vehicle 120 approaching the crossing that no train is within the first insulated section. As the train progresses the next insulated section 46 is bridged by a wheel axle and the second relay 50 is actuated, raising its armature which interconnects with the armature of relay 49 and continues to hold the green lamp open circuited. The actuation of the armature of relay 50, however, puts on the red lamp by bridging its contacts and 125 130

pleting the circuit of the red lamp 13 and the audible signal 11, warning any vehicle approaching the crossing. On arrival of the locomotive on the third insulated section 5 47, relay 51 is actuated, completing the circuit at the bridging contacts of its armature of the magnet 39, thereby actuating the armature 41 and putting the gate casings in communication with compressed air and 10 lowering the gates and preventing transit of traffic through the gate. In the meantime, through the system of interconnection of the armatures of the three relays 41, 50, 51, the red lamp and alarm continues until the last 15 wheel of the train has passed insulated section 47, when the relays are deenergized, restoring the green light and raising the gates. With the downward movement of the gate, on application of air pressure, the 20 bridging contact 26 closes contacts 27, 27* and puts on a green lamp G a determinate distance in advance of the gate to give a signal to indicate to the engineer that the gates are lowered. When the compressor is 25 in communication with the gate pistons closing vehicular traffic, the track instrument is expanded against the tension of its retracting spring and the foot 32 is moved into inoperative position and at the same time the 30 circuit to lamp R is closed by contacts 33 and 34 to indicate to the engineer that said track instrument is in inoperative position and he can proceed across the crossing. If the 35 engineer should disregard the fact that the light signals are not lighted, which indicate that the gates are up and the track instrument in tripping position, the instrument will engage the depending part of the arm 40 37 to put on the brakes or otherwise stop the train. This will prevent the train from striking a vehicle stalled on the tracks, which prevents operation of the parts, as before described.

It will be evident upon an inspection of 45 Figure 1, which shows two tracks accommodating opposite directions of railway traffic that the several relays are affected similarly by a train moving in either direction toward the gates. The circuit connections with the 50 relays and the interlocking armatures of the several relays prevent a return-to-the normal condition by holding the circuits in a signaling condition, showing danger until the train has passed the crossing and restores 55 the normal condition. It will be apparent that the invention is not limited to a single pair of tracks as any other number similarly arranged may be employed.

What I claim is:—

60 1. In a railroad crossing signal system, a plurality of insulated track sections a determinate distance from each side of the crossing, a power actuated gate at the crossing arresting vehicular travel, a plurality 65 of relays each in parallel with respective in-

sulated sections each side of the gate, including a source of electromotive force and adapted to be successively actuated by progress of the train, interlocking armatures for relays and circuit connections for progressively opening a safety signal, establishing a danger signal and cutting in power to close the gate. 70

2. In a railroad crossing signal system, a plurality of insulated track sections located 75 a determinate distance from each side of the crossing, a universal compressed air system, a pair of gates counterbalanced by counterweights at the crossing and a plurality of relays each in parallel with respective insulated sections at each side of the gate, including a source of electromotive force, said relays adapted to be successively actuated by progress of a train, and interlocking armatures for the relays, said armatures successively cutting out a safety signal, putting on 80 a danger signal, and governing application of compressed air to raise the counterweights and close the gates. 85

3. In a railroad crossing signal system, a plurality of insulated track sections located 90 a determinate distance in advance of the crossing at each side thereof, counterweighted gates at the crossing, an electromagnet for applying compressed air to close the gates, a plurality of relays each connected with its 95 respective sections, successively controlling signals from safety to danger and operating the electromagnet to apply compressed air and lower the gates and a valve controlled by 100 the deenergization of the electromagnet for automatically bleeding the air pipes and rendering inoperative a danger signal along the track and at the crossing. 105

4. In a railroad crossing signal system, a plurality of insulated track sections a determinate distance at each side of the crossing, a plurality of relays, a pair of compressed air operated gates at the crossing, a signal circuit and a magnet controlled by the relays, a compressed air valve operated by the magnet for lowering the gates, parallel connections to each relay from respective insulated sections, said relays adapted to be energized by a train to operate the magnet and 110 lower the gate and a track instrument responsive to the compressed air, said track instrument having a trip foot to engage a valve controlled detent on a locomotive and arrest the train on failure of the compressed 115 air mechanism to function properly. 120

5. In a railroad crossing signal system, power operated gates to bar or permit vehicular transit over the crossing, train and highway signals associated therewith, a pair 125 of tracks with insulated sections a determinate distance each side of the gates, relays connected across the tracks and a source of electromotive force in series therewith and in parallel with respective insulated 130

track sections of the track at the sides of the gates to control operation of said gates and signals progressively by said relays by progress of trains on the track.

- 5 6. In a railroad crossing signal system, a pair of pneumatically operated gates, an air compressor to operate the same, an electromagnet, a pair of valves controlled thereby to operate the gates, a plurality of insulated 10 track sections a determined distance from each side of the crossing, a plurality of relays having interlocking armatures and including a source of electromotive force, each

relay being in parallel with respective insulated sections each side of the gate and is adapted to be successively actuated by progress of a train to progressively change a clear signal to danger and to energize the electromagnet to supply air pressure to the gates by means of one of said valves on approach of a train and means to bleed the air and raise the gates by means of the other of said valves on passage of the train. 20

In testimony whereof I affix my signature.

SAMUEL A. ORR.
